(57)

CLAIM

The ornamental design for a vehicle wheel, as shown and described.

DESCRIPTION

FIG. 1 is a front view of a vehicle wheel showing my new design;

FIG. 2 is a front perspective view thereof; and,

FIG. 3 is a rear view thereof.
The broken lines show portions of the vehicle wheel which form no part of the claimed design.**1 Claim, 3 Drawing Sheets**| (56)	References Cited
